UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

ELASTIC-FLUID TURBINE.

1,156,627.

Specification of Letters Patent. Patented Oct. 12, 1915.

Application filed April 27, 1915. Serial No. 24,317.

To all whom it may concern:

Be it known that I, RICHARD H. RICE, a citizen of the United States, residing at Lynn, county of Essex, State of Massachusetts, have invented certain new and useful Improvements in Elastic-Fluid Turbines, of which the following is a specification.

The present invention relates to elastic fluid turbines and has for its object to provide an improved arrangement of horizontal turbine wherein the condenser for the machine is located directly beneath the casing thereof, the turbine and condenser having in part a common casing.

For a consideration of what I believe to be novel and my invention, attention is directed to the accompanying description and the claims appended thereto.

In the accompanying drawing, Figure 1 is a side elevation partly in section of a turbo-generator set, and illustrates one form or embodiment of my invention, and Fig. 2 is a section taken on line 2-2, Fig. 1.

Referring to the drawing, 3 indicates a horizontal elastic fluid turbine, here shown as of the impulse type having a horizontally divided cylindrical casing.

4 indicates the wheel of the final or last stage. It may drive any suitable load and is shown as direct connected to an electric generator 5. The final stage of the turbine exhausts into the chamber 6 from whence the elastic fluid passes directly to the condenser 7. By this arrangement I avoid the use of the exhaust conduit usually employed between the turbine and condenser casing, and at the same time provide a very direct passage for the steam which is of large area and hence offers practically no opposition to the passage thereof. The condenser is of the surface type and the body of its casing comprises two principal parts 8 and 9. The part 8 is made integral with and forms in substance a part of the turbine casing proper.

In other words, it forms a part of the usual exhaust chamber of the turbine and also a part of the steam receiving chamber of the condenser. It has a lower wall 10 which is preferably curved concentric with the turbine shaft so that the outer tubes will all be located at substantially the same distance from the turbine axis. By this means the length of the steam paths to the various tubes will be more nearly uniform than heretofore, thereby improving the condenser

action and avoiding restrictions, pockets, etc. The part of the condenser also has two inclined side walls 11 which terminate in flat surfaces or flanges 12 for supporting the upper and removable half 12^a of the turbine casing.

13 are supporting feet which are common to the turbine and condenser. Ordinarily they will be supported by suitable longitudinally extending floor beams. These feet may extend along the whole length of the condenser or not as desired. The generator is supported from underneath, as at 13^a. The part 9 of the condenser casing has its upper and lower walls 14 and 15 curved to conform to the turbine casing and extends up on each side of the turbine casing as indicated, chiefly by the dotted lines in Fig. 1. In other words, this portion of the condenser partly surrounds the turbine casing, a feature which makes for compactness, as will be readily seen.

16 and 17 indicate the removable condenser heads between which, and the condenser casing proper, are clamped the tube sheets 18 that support the horizontal condenser tubes 19 in the usual manner. The pipes for the cooling water are indicated at 20 and 21 and that for drawing off the condensate at 22.

The condenser tubes are relatively long, as is necessary to get the most effective condensing action, but by placing them horizontally and underneath the turbine they do not increase the overall length of the unit. By so arranging them it is possible to inspect or renew them without disturbing the turbine or generator. Furthermore, the condenser does not occupy space that can be used for other purposes. Ordinarily the turbine and condenser will be so positioned that the latter is situated below the floor beams and hence is out of sight, thereby improving the appearance of the unit as a whole.

The turbine and generator are united by an annular or bridging member 23 which also carries the middle bearing 24 for the turbo-generator shaft. The end bearings for the shaft are carried by the outer heads of the turbine and generator respectively. It will also be noted that the condenser extends under said member, and in this manner I make use of space which would otherwise be wasted. The condenser tubes may be

arranged in any desired manner, but I prefer the arrangement shown in Fig. 2, because all the tubes in a given row will be located at the same distance from the shaft axis and 5 hence the frictional resistance to the passage of steam will be substantially the same at every point.

By the above arrangement it will be seen 10 that the condenser tubes 19 are brought very close to the wheel or wheels of the last stage of the turbine and that a connecting conduit is avoided. This means that the vacuum of the final wheel chamber will be that of the condenser proper as the losses which occur 15 in the usual conduit connecting the turbine to the condenser are avoided. This results in a better efficiency of the turbine and decreased losses in the condenser system. The arrangement also has the advantages that it 20 secures maximum compactness, effecting a substantial economy in space, while at the same time the condenser tubes are readily accessible by removing the heads 16 and 17.

In accordance with the provisions of the 25 patent statutes, I have described the principle of operation of my invention, together with the apparatus which I now consider to represent the best embodiment thereof; but I desire to have it understood that the apparatus 30 shown is only illustrative, and that the invention can be carried out by other means.

What I claim as new and desire to secure by Letters Patent of the United States, is:—

- 35 1. The combination with a horizontal elastic fluid turbine, of a condenser therefor comprising a casing arranged directly beneath the turbine and having a contour which conforms to that of the turbine casing.
- 40 2. The combination with a horizontal elastic fluid turbine, of a condenser therefor located directly beneath the turbine casing, said condenser having a portion of its casing formed integral with the turbine casing.

3. The combination with a horizontal elastic fluid turbine, of a condenser therefor located directly beneath the turbine casing and having a contour which conforms to that of the turbine casing, the portion of the condenser casing adjacent the final stage of the 50 turbine being formed integral with the turbine casing so that the tubes of the condenser are all exposed at one end directly to the final wheel chamber of the turbine.

4. The combination with a horizontal elastic fluid turbine, of a condenser therefor located directly beneath and shaped to conform to the outline of the turbine casing, said condenser casing being in direct communication with the final wheel chamber. 55

5. The combination with a condenser having supporting feet and flanges on opposite sides, of an elastic fluid turbine having a removable cover which is seated on said flanges. 60

6. The combination with a turbine and generator which are connected by a bridging member, of a condenser which extends parallel with the turbine and partially surrounds it and said member, and feet on opposite sides of the condenser for supporting it and the turbine. 70

7. The combination with a horizontal shaft turbine having an exhaust chamber, of a condenser which extends parallel with and 75 partially surrounds the under side of the turbine, the exhaust chamber of the turbine and steam chamber being in direct communication.

8. The combination with a horizontal shaft 80 turbine having an exhaust chamber at one end, of a condenser which extends parallel with and partially surrounds the under side of the turbine, one end of which forms a part of said exhaust chamber.

In witness whereof, I have hereunto set my hand this 23rd day of April, 1915.

RICHARD H. RICE.
